US0D1026817S

(12) **United States Design Patent** (10) **Patent No.:** **US D1,026,817 S**
(45) **Date of Patent:** **** May 14, 2024**

(54) **INVERTER**

(71) Applicant: **VOLTRONIC POWER TECHNOLOGY CORP.**, Taipei (TW)

(72) Inventors: **You-Sheng Chiang**, Taipei (TW);
Yu-Cheng Lu, Taipei (TW); **Juor-Ming Hsieh**, Taipei (TW)

(73) Assignee: **VOLTRONIC POWER TECHNOLOGY CORP.**, Taipei (TW)

(**) Term: **15 Years**

(21) Appl. No.: **29/806,112**

(22) Filed: **Sep. 1, 2021**

(30) **Foreign Application Priority Data**

Jul. 28, 2021 (TW) 110303917

(51) **LOC (14) Cl.** **13-02**

(52) **U.S. Cl.**

USPC **D13/110**

(58) **Field of Classification Search**

USPC D13/103, 107, 119, 152, 158, 177, 184

CPC H01R 13/52; H01R 13/6675; H01B 1/50;

H02J 7/00; G06F 1/1632

See application file for complete search history.

(57) **CLAIM**

The ornamental design for an inverter, as shown and described.

DESCRIPTION

FIG. 1 is a front, right side, top perspective view of an inverter, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, left side, bottom perspective view thereof; and,

FIG. 9 is a front, right side, top perspective exploded view thereof showing the inverter that is disassembled into a main body, a battery pack, and a bottom cover.

The dashed broken lines in the drawing depict portions of the inverter that form no part of the claimed design.

1 Claim, 8 Drawing Sheets
